UNITED STATES PATENT OFFICE.

RUFUS A. SIMPSON, OF OAKLAND, CALIFORNIA.

BUTTER-CUTTING MACHINE.

Application filed January 19, 1921. Serial No. 438,405.

To all whom it may concern:

Be it known that I, RUFUS A. SIMPSON, a citizen of the United States, residing at the city of Oakland, in the county of Alameda and State of California, have invented certain new and useful Improvements in Butter-Cutting Machines, of which the following is a specification.

This invention relates to improvements in butter cutting machines and more particularly to that type of machine which has a movable cutting head carrying cutting wires which are advanced longitudinally into a mass of butter. In cutters of this character, the head is provided with a number of spaced crossed wires which make the vertical and horizontal longitudinal cuts. These wires require considerable effort to force them into the mass of butter and my present invention aims to secure a more effective means for advancing the head but which at the same time allows the latter to move rapidly in the opposite direction after the butter has been cut.

Another object of the invention is to provide means whereby the weight of blocks of cut butter may be more accurately regulated than in the present style of butter cutters which depend on securing the correct weight by cutting the butter to given dimensions. With machines of the type herein illustrated, it is possible by exerting a pressure on the cutter head to compress the butter to such an extent that when the prints are cut off there is a considerable variation in weight.

Another difficulty with the present cutter is that on the releasing of the cutting head the butter assumes its uncompressed condition whereby the face of the uncut block of butter is slightly forced back past the plane of the cut-off wire so that on the upward movement of the latter a thin shaving is taken off of the face of the packed butter. My present invention has as another object the elimination of the above mentioned defect by enabling the same pressure to be exerted on the uncut block of butter each time the head is advanced so that when once the required movement is secured for a given weight, this weight may be accurately maintained.

With these and other objects in view, my invention consists in certain novel features

of construction, combinations and arrangement of parts hereinafter described and more specifically pointed out in the appended claims, it being understood that changes in the form, proportion, size and minor details of construction within the scope of the claims may be resorted to without departing from the spirit of the invention or sacrificing any of the advantages thereof.

Reference being had to the accompanying drawings forming a part of this specification:

Figure 1 is a view in end elevation of the cutter head and receiving table which is movable therewith showing my invention applied thereon.

Figure 2 is a view in plan of the same.

Figure 3 is a view in side elevation.

Figure 4 is an enlarged sectional view through the driving and locking mechanism for the cutter head.

Figure 5 is a view in section on the line 5—5 Figure 2.

Figure 6 is a bottom plan view of the receiving table.

Figure 7 is a view in section on the line 7—7 of Figure 2 looking in the direction of the arrows.

Referring to corresponding parts in the several views by the same numerals of reference: my invention comprises a table consisting of the side members 1 which are supported on legs 2. Attached to the upper surface of the side members 1 are tooth rack bars 3 and a guide bar 4 which slightly overhangs the inner face of the angles 1, and on which is movably mounted the cutting head denoted in general by A. The latter comprises a rectangular frame 6 the lower member of which is attached to angles 7 which extend parallel to the side bars 1. Mounted on these angles to the rear of the cutter head frame are brackets 8 in which is secured a non-revolvable sleeve 9. Revolvably mounted in the latter is a shaft 10 to which are secured toothed pinions 11 which mesh with the rack bars 3 and by their rotation moves the cutter head in a forward or rearward direction.

Keyed to the shaft 10 is a disc 12, to the inner face of which is pivotally mounted toothed pinions 13. Disc 12 is revolvably mounted within a non-rotatable disc 14 which is held in a fixed position by later-

ally extending arm 16, the outer end of which is held by the bolt 17. Disc 14 is provided with the internal gear teeth 18 which are engaged by pinions 13. The inner circumference of these pinions in turn engage a pinion 19 which is revolvably mounted on shaft 10 adjacent to the face of the disc 12. Slidably mounted on the shaft 10 is a double ended crank 20 having the operating handles 21. This crank on its rear side is provided with a toothed clutch 22 and on its forward side with a similar toothed clutch 23. The clutch teeth 22 are adapted to engage similar teeth 24 formed on the pinion 19, while the clutch teeth 23 engage similar teeth 26 formed on the collar 27, keyed to the outer end of shaft 10. The relation of the various sets of teeth just described is such that one set is engaged just before the other set is disengaged, and one is operative in the opposite direction to the other.

Integrally formed with the crank arms is a ring 30 having ratchet teeth 31 on its outer face which teeth are engageable by the pawls 32 and 33. The latter pawl is provided with a weight 34 by which it is urged into contact with the ratchet teeth. The engagement of the pawls and teeth is such that a bite is secured for every half pitch of the ratchet teeth. Extending radially from the disc 14 are two arms denoted by 35 and 36. To the former the pawls 32 and 33 are pivotally mounted, pawl 32 being attached to a pin 37 which extends through the bearing arm and on the rear thereof is attached a weight 38 which tends to move the pawl into engagement with the ratchet teeth. The pawl 32 is so positioned that when it is lifted from the ratchet teeth it contacts with the projecting portion of the pawl 33 and disengages it also. These pawls are normally held out of engagement with the ratchet by means of the mechanism next described.

Back of the cutter-head is a tilting table denoted generally by B, on which the cut butter is received. This head comprises the frame 40 having handles 41 and central cross bar 42. At the bottom, the frame has forwardly projecting arms 43 to which are removably secured the receiving board 44. Within the frame 40 is an adjustable sub-frame 45 consisting of the vertical side angles 46, cross connecting members 47, the central connecting member which is loosely mounted on the end of a screw 48. The latter extends through and is in threaded engagement with a bushing 49, which is slidably mounted in a hub 50 on the back of cross bar 42. The screw has a hand wheel 52 which enables the sub-frame to be adjusted longitudinally with respect to the cut-off mechanism. Extending outwardly 65 from the cross bar 42 is a T-headed pin 53

the head of which serves as a fulcrum for the lever 54. The latter is provided with an opening which straddles the hub 50 and shallow notches on the inner face thereof are engaged by pins 55 extending radially 70 from the bushing 49.

Extending outwardly from the frame 40 is a slotted guide 56, the lever passing through the slot thereof with its outer end positioned adjacent the weighted member 75 38, the latter having a depending arm 57 with which the outer end of the lever is adapted to contact. The end of the guide 56 is bent laterally as shown at 58 and slidably mounted in a hole therein is a pin 59, 80 the inner end of which is provided with a clevis 60, pivotally mounted on the lever. A heavy compression spring 61 is interposed between the clevis and the bent portion 58, this spring tending to push the lever and 85 consequently the sub-frame towards the cut-off head. Attached to the upper edge of the lever is an index finger 62 and the bracket has an indicating mark 63 with which this finger may be brought into alignment.

Extending outwardly from the rear of the side bars of the frame 40 are hooks 90 which embrace the sleeve 9. These hooks serve to position the frame in a longitudinal direction but do not rest on the sleeve when the frame is in its erect position. In the latter position the forward extending arms 43 rest on adjustable screws 91 and the upper end of the frame is held against tilting in a rearward direction by means of a spring bar 93 100 which extends rearwardly from the cutter head A. This construction enables the tilting frame to be vertically adjusted by the screws 91 so that it is just the right height to receive the cut butter. The spring bar 105 has a latch 97 on its outer end which engages the outer corner of the upper cross bar of the tilting frame. To release this latch I provide a pivotally mounted lever 94, the upper edge of which contacts with the under surface of the latch. This lever extends through a yoke 95 and is provided with a handle 96 positioned adjacent and under one of the handles 41. This enables the operator in handling the frame to grasp the handle 96 at the same time that he grips the handle 41 and thus by pressing the two together releasing the frame preparatory to tilting it.

Extending outwardly from the side of frame 6 is a boss 65 to the side of which is attached a strap 67. The upper end of this strap is bolted to the side of the frame as shown at 68 and the lower end extends under the frame angle and is there provided with an adjustable guide 70 to prevent the 115 frame from raising upwardly. The screw 120 125 130 which holds arm 16 is used to connect the strap 67 to the boss 65. The under side of the frame 6 is provided with guides 71 which engage the bar 4, this bar thus serv-

ing as a guide for the cutter head and tilting table.

On the side of the frame 6 are vertical gibs 72 on which is slidably mounted the 5 blocks 73. These blocks have off-set portions 74 which extend in front of the side bars of the frame and are provided with tensioning devices 75 for the cutting-off wire 74'. This wire extends from one block 10 73 to the opposite one and by its tension serves to hold the sliding blocks on the gibs. The blocks are moved by means of links 75 which are pivotally mounted therein and have their other ends pivotally connected to 15 the lever arms 76. The latter are pivotally mounted on the upper cross bar of frame 6 near the center thereof and are provided with connecting segmental gears 77 so that the two arms move in unison. The guide 20 blocks have upwardly extending arms 78 that are connected across their upper end by means of a link 79. One of the connecting links 75 has a lug 80 for contact with the disengaging lever 81, the latter being pivotally mounted in the arm 36. One end of the 25 lever 81 is engaged by the lug just mentioned while the other end extends under the weighted arm 38 so that when the cut-off wire descends the lever 81 is moved to throw 30 the weighted arm upwardly and thus release the pawls from the ratchet.

In front of the frame 6 and held therein is a wire frame 82 having cross wires 83 for the purpose of dividing the block of butter 35 in a longitudinal direction. On the forwardly projecting arms 43 of the tilting frame is mounted a removable butter receiving board 44. To hold this board in position, I attach members 85' to the under side 40 of the board, these members lying adjacent the arms and serving to position the board laterally in the frame. Clips 85 extend from these members over the arms and have screws 86 which when tightened, clamp the 45 board on the arms and yet permit its easy removal by slightly releasing the holding screws. This construction is desirable in as much as the wooden parts of the machine require to be frequently cleaned and soaked 50 in strong brine. For this purpose they must be removed from the machine and the construction herein described allows this to be quickly and conveniently accomplished. The construction also enables the board to be 55 moved towards the rear end of the cutting frame so that only a very small slot is left therebetween for the travel of the cut-off wire. By keeping this slot of a width not much greater than the diameter of the cut-off 60 wire, prevents waste of butter due to the breaking out of the lower edge when the cutting wire is driven through the block.

A block of butter is denoted by 87 and in use the cutting frame is advanced towards 65 this block of butter by turning the crank

handles 21 in the direction of the arrow in Figure 3. This causes the clutch teeth 23 and 26 to disengage and the teeth 22 and 24 to engage. Shaft 10 is then driven through pinions 19 and 13 to gear 18 and 70 disc 14. The pinions 11 engage the rack bars and thus move the frames A and B to the right as viewed in Figure 3. As the frame is advanced the crossed wires cut through the butter 87 and the latter slides 75 on to the bottom board 44. The ends of these cut sections then come in contact with the off-bearing boards 88, and further movement of the handles cause the butter to exert a pressure on the sub-frame. This pressure 80 is sufficient to somewhat compress the butter and if the amount of compression varies for the different cut-off operations, then the weight will correspondingly vary and the different prints of butter will have different 85 weights. To overcome this, is the object of my invention, by providing that the pressure exerted each time will be uniform. After the butter comes in contact with the off-bearing boards of the sub-frame, the 90 continued movement of the crank handles causes the sub-frame to be pushed rearwardly and the sleeve 49 to slide in the hub 50. This movement correspondingly moves the lever 54 so that its outer end which is 95 normally in contact with the arm 57 is released therefrom and allows the weight to move the pawl into contact with the ratchet. Thus the pawl only contacts with the ratchet during the time of final movement of the 100 operating crank. The movement of the lever is resisted by the spring 61 and the amount of movement is indicated by the pointer 62 and in use the operating handles are turned each time until this pointer is 105 opposite the indicating mark 63. The lever 54 is in effect a scale arm to weigh the pressure which is exerted against the butter. If any adjustment is required, it may be made by turning the wheel 52 so as to change the 110 relative position of the sub-frame or by laterally adjusting the index finger 62.

In the past I have found a tendency on the part of the cutter head to move backwardly due to several causes, including the compressive action of the butter and the bowing action of the wires. These wires are in high degree of tension and are bowed backwardly as the head is advanced so that when the handles are released, the tendency of this 115 bow in the wire is to return the head a slight distance in a rearward direction. This is overcome by the pawls engaging the ratchet 31, so that when the handles are freed in order to operate the cutting off wire, the entire head and associated parts are firmly held in position. When the index finger has been brought to its correct position, the levers 76 are moved in a downward direction causing the links 75 to slide the blocks 73 130

downwardly on their guides and wires 74 to cut off the prints of butter. At the extreme downward position of the cut-off wire, lug 80 contacts with the end of lever 81, raising 5 the weight 38 to release the ratchet. The frame is then free to move and the spring 61 exerts a pressure on the lever 54 which now acting on the pin 55 as a fulcrum draws the frame B and the cut-off head A a slight 10 amount in a rearward direction. The tilting table is then released by lifting up on lever 94 and tilting it in a rearward direction to allow the cut-off butter to be removed. Cut-off wire 74 is then raised, releasing lever 81 15 and allowing the pawls to drop. But when the tilting table is restored back of latch 97 the end of the lever 54 contacts with arm 57 and lifts the pawls. The head may then be freely moved in either direction without interference by the ratchet.

When the heads are to be moved rearwardly, the handles are turned in the opposite direction from the arrow in Figure 3, which action causes the teeth 22 and 24 to 25 slide out of engagement and the other set into contact.

Having thus described my invention, I claim as new and wish to cover by Letters Patent:

- 30 1. A butter cutter, comprising, in combination, a movable head, a driving shaft therefor, a planetary gear system on said shaft, a drive pinion for said system, an operating crank adapted for engagement with 35 either the pinion or the shaft, said crank provided with normally inoperative ratchet mechanism, means adapted to throw the ratchet mechanism into action by the pressure of the head against the butter.
- 40 2. A butter cutter, comprising, in combination, a head, a cut-off mechanism, a drive shaft for moving the head against the butter, a normally inoperative ratchet mechanism for holding the shaft from reverse 45 movement, means operable by the pressure of the head against the butter for throwing the ratchet mechanism into action, and means

operable by the cut-off mechanism for releasing the ratchet mechanism.

3. A butter cutter, comprising, a cutter 50 head movable against the butter, a follower gauge board for contacting and receiving the cut butter, and means for indicating when said gauge board exerts a given pressure against the butter. 55

4. A butter cutter, comprising, a cutter head, driving means for moving said head against the butter, a follower gauge board limiting the movement of the head with respect to the butter, indicating means for 60 showing a uniform pressure against the gauge board, and ratchet means for holding said driving means when the desired pressure is reached.

5. A butter cutter, comprising, in a cutter 65 head, a cut-off device, driving means for moving said head against the butter, a follower gauge board for limiting the movement of the head with respect to the butter, indicating means for showing a uniform 70 pressure against the gauge board, ratchet means for holding said driving means when the desired pressure is reached, and means operable by the cut-off device for releasing the ratchet mechanism. 75

6. A butter cutter, comprising, a cutter head, a tilting receiving table, a gauge board carried by the table, a compression spring for holding the board in an extended position, a pressure indicator operable by the 80 backward movement of the board caused by the butter contacting therewith and reacting against the compression of said spring, and a receiving platform carried by said table, and means detachably and adjustably securing the platform to the table. 85

7. In a butter cutter, a tilting table adapted to support an adjustable sub-frame and a gauge board, the latter adapted to bear against the sub-frame for operating the pressure indicating means for the purpose set forth. 90

In testimony whereof I affix my signature,
RUFUS A. SIMPSON.
